(57) **CLAIM**

The ornamental design for a bridging clip with ribs, as shown and described.

DESCRIPTION

FIG. 1 is a top perspective view of a bridging clip with ribs, showing our new design;

FIG. 2 is a bottom perspective view of the bridging clip with ribs of FIG. 1;

FIG. 3 is a front elevational view of the bridging clip with ribs of FIG. 1, the rear elevational view being a mirror image thereof;

FIG. 4 is a left elevational view of the bridging clip with ribs of FIG. 1;

FIG. 5 is a right elevational view of the bridging clip with ribs of FIG. 1;

FIG. 6 is a top plan view of the bridging clip with ribs of FIG. 1;

FIG. 7 is a bottom plan view of the bridging clip with ribs of FIG. 1; and,

FIG. 8 is a top perspective view of the bridging clip with ribs of FIG. 1 shown in conjunction with a horizontal bridging member and a vertical stud.

The broken lines shown in the drawings are included for purposes of illustrating portions of the bridging clip with ribs or environmental structure that form no part of the claimed design.
